[57] CLAIM

The ornamental design for a combination hand tool, as shown and described.

DESCRIPTION

FIG. 1 is a top, left, front perspective view of a combination hand tool showing my new design, in a closed position;

FIG. 2 is a rear elevational view thereof;

FIG. 3 is a right side elevational view thereof;

FIG. 4 is a top plan view thereof;

FIG. 5 is a bottom plan view thereof;

FIG. 6 is a top left front perspective view thereof, with the jaws in an open position;

FIG. 7 is a rear elevational view thereof with the jaws in the open position;

FIG. 8 is a left side elevational view thereof with the jaws in the open position;

FIG. 9 is a right side elevational view thereof with the jaws in the open position;

FIG. 10 is a top plan view thereof with the jaws in the open position;

FIG. 11 is a bottom plan view thereof with the jaws in the open position; and,

FIG. 12 is a front elevational view thereof, with the handles in an alternate position and with the implements in an open position.
